United States Patent Office

Des. 227,604

Patented July 3, 1973

227,604

AMPHIBIAN AIRCRAFT

Richard A. Vrooman, 3551 Mentone Ave. 4,
Los Angeles, Calif. 90034

Filed Jan. 27, 1971, Ser. No. 110,358

Term of patent 14 years

Int. Cl. D12—07

U.S. Cl. D71—1

FIG. 1 is a right side elevational view of an amphibian aircraft embodying my design, and a mirror image of the other side;

FIG. 2 is a front elevational view;

FIG. 3 is a rear elevational view;

FIG. 4 is a partial top plan view, with a portion of the starboard wing being omitted for ease of illustration the design being symmetrical about the longitudinal axis of the aircraft; and

FIG. 5 is a partial bottom plan view with a portion of the seaboard wing being omitted for ease of illustration.

I claim:

The ornamental design for an amphibian aircraft, as shown and described.
